(57) **CLAIM**

The ornamental design for a novelty having weighted terminus, as shown and described herein.

DESCRIPTION

FIG. 1 is a bottom plan view of my new design for a novelty having weighted terminus;

FIG. 2 is a top plan view thereof;

FIG. 3 is a right side elevational view thereof, the side opposite being a mirror image of the side shown;

FIG. 4 is a front elevational view thereof;

FIG. 5 is a rear elevational view thereof;

FIG. 6 is a right side elevational view showing a second embodiment of my design, the side opposite being a mirror image of the side shown;

FIG. 7 is a front elevational view thereof;

FIG. 8 is a rear elevational view thereof;

FIG. 9 is a bottom plan view thereof;

FIG. 10 is a top plan view thereof;

FIG. 11 is a top plan view showing a third embodiment of my design;

FIG. 12 is a bottom plan view thereof;

FIG. 13 is a right side elevational view showing a second embodiment of my design, the side opposite being a mirror image of the side shown;

FIG. 14 is a front elevational view thereof; and,

FIG. 15 is a rear elevational view thereof.

The portions shown in broken lines are for illustrative purposes only; and form no part of the claimed design.
